UNITED STATES PATENT OFFICE.

HENRY R. BUTTERFIELD, OF WATERVILLE, MAINE.

VACUUM-CORE FOR ELECTRICAL HEATING DEVICES.

SPECIFICATION forming part of Letters Patent No. 447,127, dated February 24, 1891.

Application filed June 25, 1890. Serial No. 356,653. (No model.)

To all whom it may concern:

Be it known that I, HENRY R. BUTTERFIELD, a citizen of the United States, residing at Waterville, in the county of Kennebec and State of Maine, have invented certain new and useful Improvements in Vacuum-Cores for Electrical Heating Devices; and I do hereby declare the following to be a full, clear, and exact description of the invention, such

as will enable others skilled in the art to which it appertains to make and use the same.

Heretofore resistance-coils forming part of an electric circuit have been employed for generating heat in radiators, cookers, frying-pans, flat-irons, and other electric heating devices, the coil or equivalent resistance being commonly located within the hollow shell of the heater or inclosed in a recess thereof, but always in contact with the air, and thereby liable to oxidation and the possibility of leakage. To obviate these defects I make use of a removable hollow shell, which is exhausted of air and contains the resistance, the latter being, therefore, *in vacuo*. This core and contents are received within the calorific device or article, or some hollow part thereof, and heated by the passage of the electric current.

In the accompanying drawings, Figure 1 represents a side elevation, partly broken away, of a tailor's goose provided with my improved vacuum-core and resistance as a means of heating it. Fig. 2 represents in perspective the core and its tray detached. Fig. 3 represents a similar view of said core with the side partly broken away, and Fig. 4 represents an enlarged longitudinal section of said hollow core, the middle part being broken away.

A designates the hollow body or shell, and A' the handle of a tailor's goose, which I have selected to illustrate my invention, although any other heating or heat-applying article or structure would answer as well.

B designates a removable flat plate or tray, which slips endwise into and out of said shell, and has secured on it a hollow cylindrical core C, inclosing a vacuum. To allow the production of the latter, said core is provided at one end with a steam-inlet pipe c and at the other end with an air-outlet opening c' and a water-outlet cock c². There is also a

transverse partition I, which cuts off the extremity of the interior of said core, forming a chamber J, and provided with an opening i in line with c'. Both these openings are 55 screw-tapped and receive the same screw-plug c³. The steam-inlet pipe c is similarly screwed into an opening of said core and may be so turned therein by hand or any convenient implement as to cut off the steam. 60

To produce a vacuum the steam is first let in through said inlet and the plug c³ removed to allow the expulsion of the air. The steam-inlet pipe c is then turned to cut off the supply of steam. The plug c³ is screwed back to 65 close opening c', but not opening i. The core is cooled to reduce the steam to water and turned until the water runs into the space J. The screw-plug c³ is screwed into partition I, closing opening i and bottling the water in 70 said space. The water-outlet cock is opened and the water allowed to run off through the same, then closed again, and the vacuum is for practical purposes complete. Even if air should enter through said cock as the last of 75 the water escapes, it cannot pass the partition I. Within this vacuum a resistance-coil D is wound spirally, as shown, or arranged in any other convenient way, its ends being by preference near each other at one end of said 80 core, and held by binding-posts G G', which also hold the circuit-wires H H'. The ends of the core C are provided with journals K, which are supported in bearing-standards F, raised on tray B, allowing said core to be 85 turned on its longitudinal axis in order that the water may run through opening i into space J, and again, after another turning from this latter space, through the water-outlet cock.

I do not confine myself to any particular 90 shape of core or arrangement and construction of resistance, although I prefer those which I have shown and described. Instead of placing the resistance in a vacuum I may fill the interior of the hollow core with any 95 non-combustible gas which is incapable of acting chemically on the resistance; but a vacuum is better.

I am of course aware that electric lamps are often provided with resistances inclosed 100 *in vacuo* to produce light without appreciable combustion; also, that this has sometimes

been done for the supplemental purpose of regulating the light. These are not calorific devices, and I do not claim them.

Having thus described my invention, what I claim as new, and desire to secure by Letters Patent, is—

1. In an electric heater, a hollow core inclosing a vacuum and a resistance which forms part of an electric circuit, the said core being provided at one end with a partition cutting off a space J, a screw-plug closing at will air-outlets in the said partition and the end wall of said core, or the latter only, a water-outlet cock from said space, and a steam-inlet into the body of the core, substantially as set forth.

2. In combination with the shell of an electric heater, a hollow core inclosing a resistance which forms part of a circuit and having journals on its ends, and a removable tray or plate provided with bearing-standards

which support said journals, allowing said core to turn axially, the said core being provided with a separated space at one end and with a steam-inlet, air-outlet, water-outlet, and plug for closing the air-inlet and the opening through the partition, all substantially as set forth.

3. A hollow core inclosing a vacuum and an electrical resistance and provided with journals, in combination with a removable tray having bearing-standards raised thereon, in which said journals are supported, allowing said core to turn on its axis, substantially as set forth.

In testimony whereof I affix my signature in presence of two witnesses.

HENRY R. BUTTERFIELD.
